Des. 2370

Edward Howard of Boston Mass,
Sellers Patent No. 2370. Dated July 24, 1866,
Design for a Watch plate

The schedule referred to in these Letters Patent and making part of the same.

To all whom it may concern:

I Be it known that I, Edward Howard of Boston in the County of Suffolk and State of Massachusetts, have originated and designed a new Pattern or configuration for Watch Plates, of which the following is a full, clear, and exact description referred being had to the accompanying drawings making part of this Specification. For the drawings,

Figure 1. represents the shape of the top of the plate as seen when the watch is open, and,

Figure 2. represents the opposite side of the plate.

The Design consists entirely of a curved outline as represented in the drawing, that is to say, at the figure or shape bounded by the outer side line or perimeter of the plate at its, and has no reference to the pivot holes, depressions or other marks on either surface of the plate. These parts are represented in order to show the main object or general principle of the construction of a watch plate, but the only feature to which this application has reference is the form or figure bounded by the line A, —

What I claim and desire to secure by Letters Patent is, The Design for a Watch Plate as represented by the perimeter or boundary line A, in the accompanying drawings substantially as herein set forth.

Witnesses.

John M. Bachelder,
Franklin Hunt.

Edward Howard
